UNITED STATES PATENT OFFICE.

STEFANO PITTLUGA, OF LOS ANGELES, CALIFORNIA.

SYRUP-FILLER FOR FRUIT-CANS.

1,072,771.

Specification of Letters Patent. Patented Sept. 9, 1913.

Application filed August 5, 1912. Serial No. 713,472.

To all whom it may concern:

Be it known that I, STEFANO PITTLUGA, a subject of the King of Italy, having declared my intention of becoming a citizen of the United States, residing at Los Angeles, in the county of Los Angeles and State of California, have invented a new and useful Syrup-Filler for Fruit-Cans, of which the following is a specification.

10 The object of this invention is to provide means whereby cans containing food to be preserved may be automatically charged with syrup or liquor to the exact amount required to properly fill the can, practically without waste or dripping of the liquid; and whereby the work may be performed with great rapidity.

The invention comprises a machine adapted to operate simultaneously upon a plurality of cans; receiving the cans at one place, moving them in train and delivering them from the machine at another place, the liquor or syrup being introduced into the cans as the cans pass through the machine.

25 Machines of various sizes and containing various numbers of chargers may be constructed.

The accompanying drawings illustrate the invention as applied in an apparatus provided with eight chargers.

Figure 1 is a fragmental plan of a syrup-filling apparatus constructed in accordance with this invention and supplied with eight chargers, three of which are shown, one in the position where the cans are received, another in the position where the flow of liquid to the can has just commenced and the third in the position where the flow is just about to stop as the chargers are removed. The other five chargers and portions of the apparatus are broken away for clearness of illustration. Fig. 2 is a fragmental elevation viewed from the front of Fig. 1, omitting the same chargers as in Fig. 1. Fig. 3 is a fragmental elevation partly in section showing a can charger together with a fragment of the revolving frame upon which it is mounted. Parts are shown in normal closed position. Fig. 4 is a fragmental elevation mainly in axial section on line x^4-x^5 ; Figs 3, 6 and 7, with parts in the normal closed position. A partially-filled fruit can is shown in position to receive a charge of syrup. Fig. 5 is a view 55 analogous to Fig. 4 with parts in the position

they assume when the partially-filled can is raised to actuate the parts to thereby open the syrup charger. Fig. 6 is a plan view partly in section, viewed from irregular line x^6 , Fig. 4. Fig. 7 is a plan section from irregular line x^7 , Fig. 4. A portion of the valve is broken away to expose the seat. Fig. 8 is a detached fragmental section of the charger chamber on line x^8 , Figs. 4, 5 and 7, illustrating the valve seat and outlet. 60

The rotary syrup reservoir 1 is mounted centrally on the rotary shaft 2 that is driven by a pulley 3 and belt 4, and said reservoir is connected by syrup pipes 5 with open-ended charger shells 6 that are rigidly connected to the rotary shaft by the support 7 and are preferably constructed with reduced portions 8 to form shoulders 9 and valve chambers 10 and are provided with nozzles 11 at their lower ends; said valve chambers being provided with valve seats 12 and syrup ports 13, and the nozzles with lateral and vertical air vents 14 and 15; the syrup ports 13 being arranged between the valve seats 12 and the air vents. 70

In each of the chargers there is provided a valve 16 for closing the valve seat. Said valve is mounted on a hollow valve stem 17 which extends above and below the valve 16 and communicates with the air vents to conduct the air from the interior of the can to the atmospheric air; the upper end of the valve stem 17 being pivotally connected by a cross-head 18 and pins 19 with lever means comprising two levers 20 supported by their fulcrums 21 on opposite sides of the charger shell 6; said levers being of the third class and each comprising a long arm a between the valve stem and the pivot 22 which supports the connecting rod 23, and a short arm b between said pivot 22 and the fulcrum. The connecting rods 23 of said levers extend downwardly and are adjustably connected by adjusting nuts 24, 25 with a collar 26 that is in slidable relation to the charger shell 6 and is provided at its lower end with a can closure 27 which is adapted to seal the can against overflow during the filling action, said closure having on its lower side a practically non-absorbent 80 yielding gasket 28 that may be of soft rubber or other suitable material and is adapted to hermetically seal the top of each can when such can top is brought upward thereagainst for the purpose of filling. 85

110

The leverage between the valve stem and the connecting rod is preferably about 1 to 3, so that the movement of the valve stem relative to the valve seat may be three times 5 greater than the movement of the closure relative to the charging shell.

On the nozzle 11 is screwed an air vented syrup or liquor spreader 29, there being large syrup discharging ports 13 above said 10 spreader and around the lower extension of the valve stem which closely fits a central bore 30 in the nozzle and slides past the lateral air ports 14 to open the same as the can closure 27 and collar 26 are moved up 15 from the position shown in Fig. 4 to that of Fig. 5; and the valve is thus raised from the valve seat. Said liquid spreader is detachable; and spreader plates of various sizes, not shown, are provided with corresponding 20 centrally-threaded orifices 31 to screw onto the nozzle and also provided with vertical syrup ports 32 and lateral and vertical air vent ports 33, 34 to allow air to escape from the can into the atmosphere. Said plates are 25 detachable for the purpose of allowing the apparatus to be adapted to cans of different diameter, different sized spreader plates not shown, being used for different sized cans. The interchangeability of these various 30 sized spreading plates has another very important feature, however. These plates also serve as displacing means which project into the can during the filling operation so that the can may be filled while in contact with 35 the rubber gasket or closure 28. When the can is lowered away from the gasket and spreader plate, the syrup fills the can to exactly the correct amount, so as to allow for proper sealing and other conditions, to 40 which the can is subsequently subject. Each sized can requiring particular displacement, it is very valuable to have the spreader plate or displacing means easily detachable from the charger so that when the running is 45 changed from one sized can to another sized can, it is merely necessary to unscrew the former displacing or spreading means and replace such means for the particular can next to be run. Other forms of connections 50 equivalent to screw connections may, of course, be used, this being immaterial so long as the connection may be easily and quickly effected. The capacity thus acquired by applicant's machine for handling cans of 55 different kinds and capacities gives it a great advantage over the other machines which are now used in large scale canning establishments.

The collar 26 is cylindrical and is provided 60 at its lower end with a contraction 35 to fit the reduced portion 8; and a chamber 36 is formed between the collar 26 and the reduced portion 8 to receive a spring which may preferably be a soft rubber ring 37 65 supported between a seat 38 formed in the

collar and the external shoulder 9 of the shell; so that when the collar 26 moves upward on the shell the spring is compressed while the lever means is operated to raise the valve from the valve seat.

Below the level of the closures 27 there is provided a circular track comprising throughout about two-thirds of its circumference a level body 39 and at the ends of said level body lifting and lowering cam track sections 40, 41. Can-supporting tables or plates 42 are fixed on the tops of can-supporting standards 43, each of which is provided with a supporting wheel 44. Said posts are pivotally connected respectively by 80 parallel motion links 45 with knuckles 46 on the rotary shaft 2; there being guides 47 having seats 48 to support the parallel links 45 at the lower terminals of the cam portions of the track. Said guides and shoulders are mounted on a bracket 49 also fixed to the rotary shaft 2.

The knuckles 46 are adjustably fixed to the rotary shaft by set collars 50, so that they may be placed at a desired level to accommodate the height of the cans to be operated on.

The can-supporting plates 42 are equal in number to and are supported axially beneath the shells respectively, and each 95 spaced apart from its shell a considerable distance below the closure, to allow the can 51 to be inserted into the space when the parallel motion links are supported by the supporting shoulders 48 and the rise 40 of 100 the cam track is sufficient to cause the can to close such distance and to contact with the closure and force the collar up, thereby raising the valve stem, opening the valve and allowing the syrup or liquid contained in 105 the shell to flow down into the can. The air vents allow the air contained in the can to escape to make room for the liquid and as the can moves around above the track the liquid fills the can, excepting the space that 110 is occupied by the spreader plate and nozzle. When the supporting roller reaches the lowering cam track section 41 the can supporting plate is lowered, thus allowing the closure and valve stem and valve to descend, 115 thus closing the valve seat and the lateral air vents 14; and the can is withdrawn from the closure and is free to be removed from the supporting plate.

As the shaft 2 rotates the can tables are 120 periodically moved toward and from the chargers by means of the cam track and the standard wheels 44 running thereon.

The cans are respectively released as the standard wheels enter the space between the 125 sections 40 and 41. The can may thereupon be removed by automatic means, not shown, or by hand as desired and another can put in its place by automatic means, not shown, or by hand; whereupon the process is re- 130

peated with such other can, it being understood that in the meanwhile each of the can-supporting plates of the entire machine has passed from the position shown at the 5 center in Figs. 1 and 3, and onward over the track, and that the several cans are in different stages of being filled and made ready. The tubular valve stem is also provided below the top of the charger shell 6 10 with vent ports 52 that are protected by a hood 53, so that in case the upper end of the tubular valve stem should become stopped there would still be free vent through the ports 52. The said ports and hood are especially useful, however, in permitting syrup which is accidentally sucked upward through vent 17 to escape through said ports back into the charger 6 rather than through the normal air outlet at the upper end of 20 vent 17. By this means the syrup is saved and the exterior of the machine is spared from the untidy and smeared appearance which would follow if the syrup were thrown out through the normal air outlet.

25 The operation of the apparatus will be understood from the foregoing.

As the shaft 2 rotates the supporting wheels 44 of the standards successively pass from the open space between the ends of the 30 cam and ride first up the cam 40 to the level intermediate portion 39 of the cam thus forcing the top of the can against the closure, thus raising the same slightly and consequently the valve to a greater extent so 35 that the syrup flows into the can and fills it while the standard is riding over the level portion 39 of the cam. When the standard descends the lowering cam section 41 the closure and valve automatically descends 40 under gravity and pressure of the spring 37. The spreader extends below the level of the gasket and as it withdraws from the can, the syrup sinks down in the can to give room for expansion when the contents of the can 45 is heated. In this sense the spreader is intended to represent broadly any displacing means whatsoever which may project into the can during the filling operation. When the standard roller again enters the open space 50 between the ends of the cam, the can may be removed and replaced with an empty can. The work thus proceeds, a train of cans being in course of filling at all times while the apparatus is moving.

55 I claim:—

1. In a syrup filler for cans, the combination of a relatively stationary charger equipped with a valve seat at its lower end and having a syrup discharge opening 60 through said valve seat, a relatively movable sleeve surrounding said charger and guided by same, said sleeve being adapted to slide upward and downward on said charger and said sleeve having an annular gasket on its 65 lower face adapted to form a can-closure, a

relatively movable valve rod extending down through said charger, the lower end of said valve rod carrying a valve adapted to co-operate with said valve seat in the charger, a syrup spreader below said opening through 70 said valve seat, and link means connecting said sleeve with the upper end of said valve rod so that said valve may be raised off said seat when said sleeve is raised.

2. In a syrup filler for cans, a relatively 75 stationary cylindrical charger having a smaller cylindrical portion at its lower end, a valve seat on the lower end of said charger and a syrup discharge opening through said valve seat, a relatively movable sleeve surrounding said charger and guided by same, said sleeve surrounding said charger adjacent the smaller cylindrical portion of same and adapted to form a closed annular chamber around said smaller cylindrical portion, resilient means in said chamber and adapted to normally urge said sleeve downward, said sleeve also carrying an annular gasket on its lower end, said gasket 80 being adapted to form a can-closure, a relatively movable valve rod extending through said charger, said valve rod carrying a valve on its lower end adapted to co-operate with said valve seat of the charger, and link means connecting said sleeve with the upper end of said valve rod so that said valve 85 is raised off said seat when said sleeve is raised.

3. In a syrup filler for cans, a relatively 90 stationary charger having a valve seat near its lower end and a syrup discharge opening passing through said valve seat, a relatively movable sleeve surrounding said charger and guided by same, said sleeve carrying an annular gasket on its lower end, 95 said gasket being adapted to form a can-closure, a relatively movable valve rod extending down through said charger, said valve rod carrying a valve near its lower end, said valve being adapted to co-operate with said valve seat, said valve rod at its upper end being pivotally connected with arms, which arms are also connected by pins to said stationary charger, and rods connecting said movable sleeve with said arms so that 105 said valve may be raised off said valve seat on the charger when said sleeve is raised.

4. In a syrup filler for cans, a relatively 110 stationary charging vessel formed with a valve seat near its lower end and with a threaded portion projecting down beneath said valve seat, said charger having a syrup discharge opening passing through said valve seat, a relatively movable sleeve carrying an annular gasket on its lower end, said 115 gasket being of substantial annular width so as to serve as a can-closure for cans of various sizes, a valve co-operating with the valve seat on the charger, said valve being operable when said can-closure is moved, 120

and removable displacing means separate from and independent of the foregoing elements, said displacing means having a screw connection with the screw threaded projection of said charger so that different sized displacing means may be mounted onto said projection for the different sized cans which said syrup filler is adapted to fill, said discharge opening through said valve seat being directed down toward said displacing

means so that the latter also serves as a spreader for the charging syrup.

In testimony whereof, I have hereunto set my hand at Los Angeles, California, this 29th day of July, 1912.

STEFANO PITTLUGA.
